UNITED STATES PATENT OFFICE.

JOSEPH C. BECHARD, OF FALL RIVER, MASSACHUSETTS.

SPIRAL ROTARY SHIP OR SIMILAR VESSEL.

Application filed October 21, 1927. Serial No. 227,794.

My invention relates to a new and useful type of boat which spins through the water, the boat being waterproofed throughout so that water passing overhead does not enter the interior. Unlike the submarine this boat is intended for use on the water but by reason of its peculiar construction it is adapted to cut its way through waves or breakers with a minimum amount of resistance. The speed which may be attained with this model illustrated in the drawing is enormous.

It is an object of my invention to provide a boat of the ellipsoidal type wherein the outer shell is caused to revolve around on the keel, the shell having spirally disposed vanes on its surface to accelerate its speed ahead. The internal arrangement is such that the compartments within are independent of and do not revolve with the shell. A stabilizing keel is provided upon which the boat turns.

Other objects and advantages will appear from the detailed description which follows.

I attain these objects and advantages by means of the mechanism illustrated in the drawings wherein;

Figure 1 is a side elevational view of my ship showing the fins or vanes extending over the exterior.

Figure 2 is an end elevational view of the front end of the ship.

Figure 3 is an elevational view partly in cross-section showing the interior construction.

Figure 4 is a cross-sectional view of one of the ends showing the manner of mounting the ship for rotation of the exterior while the interior remains stationary.

Figure 5 is a detail view of the cross truss which secures the interior of the ship against movement with the exterior.

Figure 6 is a detail view of the stabilizing vane.

Referring to Fig. 1, 1 is the outer shell of the ship substantially ellipsoidal in design and being mounted for rotary movement on its ends 2, 3 which are journaled on the keel 4. Spirally disposed parallel vanes 5 or fins are provided on the exterior of the shell to provide traction.

The shell 1 may be constructed of wooden lagging or sheet metal or in fact any suitable material, reinforcing ribs 6 being used internally thereof to strengthen the same. 55

The longitudinal trusses 7 of which there should be at least four in number define the stationary interior of the ship within which are to be contained the motive power for propelling the ship and the passenger and other accommodations. 60

I will now describe the end mechanism by which it is possible to rotate the ship without movement of the interior compartments. As both ends are alike the description of one applies likewise to the other. 65

Referring to Figure 4, 10 and 11 are the concentric sleeves, the outer sleeve 10 being known as the drive sleeve, and the inner sleeve 11 as the stationary sleeve. A gear 12 is pressed and keyed on to the inner end of the drive sleeve and it is through this gear that rotary motion is imparted by some motive power within the ship (not shown). 70

A collar 13 is also pressed on the shoulder of the drive sleeve, having a complementary collar 14 surrounding it, the contacting surfaces having ball-bearings 15 therein. The longitudinal trusses 7 are secured at their ends to the outer collar 14 through the wooden collar 16. 75

The ends of the shell 1 are wedged between a wooden collar 17 of a shape to conform to the interior of the shell ends, and an external cap member 18. A clamping collar 19 is threaded on the drive sleeve and abuts the wooden collar 17. An outer clamping collar 20 having a flange 21 is provided externally of the cap member 18 and coacts with the clamping member 19 to seal the open ends of the shell 1. Screws or other securing means may be used to hold the last mentioned members in rigid position. 85

A cross truss member 22 having lugs 23 at its ends for securing to the longitudinal trusses 7 is provided with a semi-circular bend 24 and by means of the complementary member 25 is secured to the inner end of the stationary sleeve and prevents it from turning with the drive sleeve. 90

The outer end of the drive sleeve is internally threaded to receive the threaded

shoulder portion 27 of a collar 26. A bearing member is mounted on the shoulder of the clamping member 20 the inner ring 28 of which is rigid on said clamping member, the outer ring 29 moving independently of the same. A cap 30 having a flanged portion 31 snugly fits the periphery of the outer ring 29.

It will be noted in Fig. 4 of the drawings 10 that a clearance 32 is provided between the collar 26 and the stationary sleeve 11. The sleeve 11 has a circumferential rib 33 thereon which forms with the shoulder 27 of the collar 26 a stuffing box for receiving suitable stuffing 34.

The stationary sleeve 11 projects beyond the cap member 30 and is journaled to the ends 35 of the keel by means of the split 20 collar 36.

20 The apparatus for controlling the keel stabilizer 40 as well as the rudder 41 passes through the interior of the sleeve 11. Any suitable means may be employed for the rudder and I have shown one method of controlling the stabilizer 40. The keel 4 is of a narrow cross section, by reason of which it may be thrown off center. I have found that by employing the V-shaped member which is hinged to the front edge of the keel 30 that the keel may be stabilized. By means of the rods and bevel gears the stabilizer may be made to move in one direction or another, the two blades being fixed together. The rods 42 are provided with an eccentric wheel 35 at their lower ends which causes the blades of the stabilizer to be deflected. The rods 42 are controlled by the handle 43 acting through the gears 44, 45, the rods 46, the gears 47 and the bevel gears 48 which are secured to the upper ends of the rods 42.

Although no attempt has been here made to show the interior arrangement of the ship it may be said that in actual construction the inner stationary sleeve will be of sufficient 45 size to allow the entry of passengers at least in a stooped position. Other pipes or connections may be led into the interior of the ship through this sleeve. It is the purpose here to show a self-contained ship which 50 revolves on its keel and has propulsive force.

In operation, the driving force is applied to the driving gear from a motor or engine (not shown) whereby the drive sleeve is 55 caused to rotate carrying with it the outer shell. By reason of the ball-bearing means the longitudinal trusses do not move and the cross truss holds the inner sleeve against movement as well as insuring against the two sleeves coming together. The shell revolves 60 without any resistance offered by the motor or engine or the weight of passengers within, by reason of the trusses supported on the ball-bearing means. Of course, other types 65 of friction-reducing devices may be used

such as roller bearings. The revolution of the shell on the water causes the spiral fins or vanes to cut the water and propel the ship ahead. By reason of its tapered ends the ship is suited to readily cut through waves 70 and breakers without materially reducing its speed.

The shell may be provided with a transparent surface at some portion of its surface to provide illumination for the interior, how 75 ever, this is optional.

All that has been said above in the description of my preferred embodiment is offered by way of illustration and not limitation. I do not wish to be limited to the 80 exact structure of the preferred embodiment shown and described; or to any particular material used in the construction of parts, or to the design of parts, but desire protection as against any variations in structure which utilize the principle of my invention and fall within the purview of my invention and are within the spirit and scope 85 of the following claims:

The invention having been set forth, what 90 is claimed as new and useful is:

1. A boat comprising an imperforate shell, a keel, said shell being mounted for axial movement on said keel, concentric sleeves at each end of said shell, said shell being secured to the outer sleeve and being adapted to turn therewith, a driving means on said outer sleeve at one end of the shell, bearing members on the outer sleeves, longitudinal truss members rotatably mounted on said 95 bearing members, a cross truss means for holding said inner sleeve away from said outer sleeve, said inner sleeve being secured to the keel, and driving means secured to said tubular member for rotating said shell. 100

2. In the structure set forth in claim 1, stabilizing means on the front part of said keel, and means within said shell for controlling said stabilizing means comprising rods, bevel gears and eccentric members. 105

3. A self-contained rotary ship comprising a substantially ellipsoidal shell, a keel, means for rotating said shell on said keel, said means comprising concentric tubular members at each end of said shell, each of the inner tubular members projecting beyond the outer tubular member being secured to the keel, a flanged cap member secured to said inner tubular member, a bearing member disposed between the flange of said cap member and said outer tubular member, said shell being secured at its ends to said outer tubular member, a second bearing member secured to each of said outer tubular members interiorly of said shell and having a collar member therearound, longitudinal truss members secured to said collar members, a cross truss member secured to said horizontal truss members and secured to 115 said inner tubular member, a driving gear 120 secured to the outer tubular member, longitudinal trusses secured to said inner tubular member, a cross truss member secured to said outer tubular member, a second bearing member secured to each of said outer tubular members interiorly of said shell and having a collar member therearound, longitudinal truss members secured to said collar members, a cross truss member secured to 125 said horizontal truss members and secured to said inner tubular member, a driving gear 130

secured to said outer tubular member, whereby the shell is caused to revolve with said outer tubular member.

4. In the structure set forth in claim 1, a stabilizer secured to said keel, said stabilizer comprising a V-shaped member secured to the forward part of the keel, controlling means

within said shell, rods, bevel gears, eccentric members, said V-shaped member being actuated directly by said eccentric members. 10

Signed at Fall River, in the county of Bristol, State of Massachusetts, this fourteenth day of October, 1927.

JOSEPH C. BECHARD.
